UNITED STATES PATENT OFFICE.

EATON K. CLARK, OF SEYMORE, IOWA.

WASHING-MACHINE.

SPECIFICATION forming part of Letters Patent No. 352,734, dated November 16, 1886.

Application filed September 14, 1885. Serial No. 177,097. (No model.)

To all whom it may concern:

Be it known that I, EATON KITTRIDGE CLARK, of Seymour, in the county of Wayne and State of Iowa, have invented certain new 5 and useful Improvements in Washing Machines, of which the following is a full, clear, and exact description.

Reference is to be had to the accompanying drawings, forming part of this specification, 10 in which similar letters of reference indicate corresponding parts in both the figures.

Figure 1 is a sectional side elevation of one of my improved washing-machines, taken 15 through the line *x x*, Fig. 2, Fig. 2 is a plan view of the same.

The object of this invention is to provide washing-machines constructed in such a manner as to wash the clothes with a pressing and rubbing movement, and which shall be simple 20 in construction and convenient in use.

The invention consists in the construction and combination of various parts of the machine, as will be hereinafter fully described and then claimed.

25 A represents the wash-tub, the back, front, and end walls of which are vertical, and may be made of wood or other suitable material, and the bottom is curved upon the arc of a circle, and is made of sheet metal.

30 In bearings in the upper rear part of the ends of the tub A is journaled a shaft, B, at the center of the circle of which the bottom of the said tub is a part. To the shaft B, at the inner sides of the end walls of the tub A, are rigidly attached the ends of two arms, C, to the outer ends of which is attached a corrugated plate, D.

35 To one end of the shaft B is attached an arm, E, which is slotted longitudinally to receive the crank-pin of the crank-wheel F, attached to the end of the shaft G. The shaft G revolves in bearings in brackets or flanges H, attached to the tub A, and to its other end is attached the crank I, by means of which the machine is operated.

40 In the upper forward part of the tub A is placed a corrugated plate, J, to which, near its corners, are pivoted the lower ends of bars K. The forward bars, K, are made longer than the rear bars, are inclined to the rearward, and 45 are pivoted to the ends of the tub A near the upper ends of the shorter rear bars, which are

also pivoted to the said ends of the tub, so that the corrugated plate J will be inclined when in its lowest position, and will be horizontal, or nearly so, when swung upward into its 55 highest position, as shown in full lines and in dotted lines in Fig. 1. Below the rock-shaft B is placed an arched plate, L, the rear edge of which is attached to the rear side of the tub A.

In the rear part of the bottom of the tub A 60 is formed a gutter or trough, M, to receive the insoluble dirt that may be washed from the clothes, and which may be drawn off through an opening, N, in the side of the said tub at one end of the said trough M. The opening 65 N can be closed by a plug or faucet. The trough M is nearly covered by an inclined plate, O, a narrow space being left at the inner and lower edge of the said plate O for the dirt to settle through. The plate O serves as an 70 apron to support and guide the water as it sweeps over the trough M, to prevent the said moving water from stirring up the dirt that has settled into the said trough.

The water in the tub A can be heated and 75 kept hot by steam introduced through an opening, P, in the end of the tub A, or by other suitable means.

To the upper forward part of the curved bottom and the lower part of the narrow front side 80 of the tub A is attached a corrugated plate or board, Q, to serve as a hand rub-board for washing such parts of the clothes as may need hand rubbing.

In using the machine a sufficient quantity 85 of soap and water is put into the tub A, and the clothes to be washed are placed in the said tub between the corrugated plates D J. The crank I is then operated, which oscillates the corrugated plate D, and causes it to press the 90 clothes against the corrugated plate J and squeeze out the water, and at the same time the upward swing of the said plate J causes the clothes to receive a rubbing pressure between the said plates, so that the clothes will 95 be washed quickly and thoroughly. As the corrugated plate D moves back, the water displaced by it rises along the rear side of the tub A, strikes the arched plate L, and is projected upon the upper side of the clothes to 100 assist in washing them.

Having thus described my invention, what

I claim as new, and desire to secure by Letters Patent, is—

1. In a washing-machine, the combination, with the tub A, of the corrugated plate D, the arms C, and rock-shaft B, carrying the said corrugated plate, the slotted arm E, the crank-wheel F, and the crank-shaft G I, operating the said rock-shaft, and the swinging corrugated plate J and its supporting-bars K, substantially as herein shown and described, whereby the clothes will be washed by rubbing and pressure, as set forth.

2. The combination, with the tub having vertical vibrating arms pivoted at their upper ends adjacent to the rear end of the tub, and

provided at their lower ends with a transverse plate, of a curved plate secured transversely to the tub behind the vibrating arms, and projecting forward between said arms above the plate thereon, with its concave face downward, whereby when the arms move downward and rearward the water will be forced upward along the back to the concave under face of the curved plate, thence downward in front of the said arms upon the transverse plate, substantially as set forth. 20 25
